(57) **CLAIM**

The ornamental designs for a candle light bulb, as shown and described.

DESCRIPTION

FIG. 1 is a perspective view of a first embodiment of a candle light bulb;

FIG. 2 is a front view of the first embodiment of the candle light bulb shown in FIG. 1;

FIG. 3 is a rear view of the first embodiment of the candle light bulb shown in FIG. 1;

FIG. 4 is a left view of the first embodiment of the candle light bulb shown in FIG. 1;

FIG. 5 is a right view of the first embodiment of the candle light bulb shown in FIG. 1;

FIG. 6 is a top view of the first embodiment of the candle light bulb shown in FIG. 1;

FIG. 7 is a bottom view of the first embodiment of the candle light bulb shown in FIG. 1;

FIG. 8 is a perspective view of a second embodiment of a candle light bulb;

FIG. 9 is a front view of the second embodiment of the candle light bulb shown in FIG. 8;

FIG. 10 is a rear view of the second embodiment of the candle light bulb shown in FIG. 8;

FIG. 11 is a left view of the second embodiment of the candle light bulb shown in FIG. 8;

FIG. 12 is a right view of the second embodiment of the candle light bulb shown in FIG. 8;

FIG. 13 is a top view of the second embodiment of the candle light bulb shown in FIG. 8; and,

FIG. 14 is a bottom view of the second embodiment of the candle light bulb shown in FIG. 8.

The broken lines in the drawings illustrate portions of the candle light bulb which forms no part of the claimed design.
